Primary Examiner — Darlington Ly*Assistant Examiner* — Nasim Abdulaziz Ali(74) *Attorney, Agent, or Firm* — Nixon & Vanderhye PC(57) **CLAIM**

The ornamental design for a tire, as shown and described.

DESCRIPTION

FIG. 1 is a perspective view of a tire in accordance with our new design;

FIG. 2 is a right side elevation view thereof;

FIG. 3 is a left side elevation view thereof; and,

FIG. 4 is a front elevation view thereof.

The part of the drawings shown with a reduced tonal value, along with the broken-line perimeter, illustrates portions the tire that form no part of the claimed design.
